UNITED STATES PATENT OFFICE.

ALPHONSO TAURMAN, OF RICHMOND, VIRGINIA.

ARTICULATED PASSENGER-CAR.

1,114,552.

Specification of Letters Patent.

Patented Oct. 20, 1914.

Application filed May 27, 1913. Serial No. 770,192.

To all whom it may concern:

Be it known that I, ALPHONSO TAURMAN, a citizen of the United States, residing at Richmond, in the county of Henrico, State of Virginia, have invented certain new and useful Improvements in Articulated Passenger-Cars; and I do hereby declare the following to be a full, clear, and exact description of the invention, such as will enable others skilled in the art to which it appertains to make and use the same.

This invention relates to passenger cars of the articulated type.

The rapid and constant increase in the population of cities and towns has presented a serious problem of providing adequate transportation facilities, both urban and suburban. To accomplish the solution of such problem it has been the ordinary practice to increase the size of the individual cars so that the latter shall have greater passenger carrying facilities. But necessarily there is a limit beyond which the size of an individual car cannot be advantageously increased, such limit being determined by a number of factors well known to railroad experts, such as the width of the streets and track-ways, the nature of the electric power equipment and similar conditions.

Furthermore the constant increase in the size of cars, even when permissible under local conditions necessarily results in a vast increase in the expense of the purchase and the maintenance of the rolling stock and the

consequent discarding of many cars of low passenger carrying capacity. The result is that many street railway companies are

financially unable to bear the burden of such additional rolling stock of high passenger carrying capacity as the traffic conditions of the road might warrant. It has also been proposed to increase the passenger carrying capacity of street car lines by using cars of the type commonly known as "double deckers" but there are so many disadvantages incident to this type of car, such as the inconvenience and difficulty of ingress and egress from the upper portion of the car, the handling of the car on sharp curves,

the inability of such car to pass beneath low street bridges and the like, that its use is prohibited in many instances by local conditions.

It is my purpose in the present instance to provide a type of passenger street car which will effectually solve many of the present

day passenger transportation problems which confront street railway companies.

In carrying out my invention I provide a car of the articulated type, such car embodying essentially two end passenger carrying sections between the adjacent ends of which is flexibly suspended an intermediate passenger-carrying compartment, this compartment being supported solely by the end sections, in the sense that it is not provided with trucks or other traction devices which engage the track. In my articulated car this suspended, intermediate section is formed with closed side walls, entrance to and exit from the entire car being had through doors which are provided at the platform ends of the end compartments or sections, while the floor of the intermediate section is substantially flush with the floors of the end section so that a continuous clear aisle is formed throughout the car thereby enabling the passengers to pass through the entire articulated car without stepping into and out of wells or depressions in the floor of the car.

Still a further object of the invention is the provision of an articulated car wherein two small rolling stock units of low carrying capacity, such as are usually possessed by modern street railways, may be utilized and converted into a single unit of relatively large passenger carrying capacity by the interposition of the intermediate passenger compartment.

I also propose to provide an articulated passenger car which may be used on narrow streets, and on short sharp curves, the articulated nature of the car enabling the latter to take curves of relatively small radii and at the same time to provide improved facilities for the safety and convenience of the passengers.

With the above recited objects and others of a similar nature in view, my invention consists in the construction, combination and arrangement of parts set forth in and falling within the scope of the appended claims.

In the accompanying drawings: Figure 1 is a view in side elevation of an articulated passenger car embodying my invention. Fig. 2 is a horizontal sectional view taken through the same. Fig. 3 is an enlarged view in side elevation showing the intermediate compartment and its connection with the end sections or compartments of the car. Fig. 4 is a horizontal sectional view taken

on the line 4—4 of Fig. 3. Fig. 5 is a similar view taken on the line 5—5 of Fig. 3. Fig. 6 is a vertical cross sectional view taken on the line 6—6 of Fig. 4. Fig. 7 is a sectional view taken on the line 7—7 of Fig. 4. Fig. 8 is a sectional view taken on the line 8—8 of Fig. 4. Fig. 9 is a top plan view of the roof portion of one of the end compartments and the adjacent end of the intermediate compartment, with a portion broken away. Fig. 10 is a sectional view taken on the line 10—10 of Fig. 9. Fig. 11 is an enlarged detail view showing the manner of connecting the sill plates and platform plates.

Referring now to the accompanying drawings in detail, the letters A and B indicate the two end sections or compartments of my improved car, and I wish it to be understood that these end sections may be in the nature of relatively small single cars, such as usually form part of the rolling stock equipment of street railways. And furthermore, as will be seen by reference to Fig. 1, 20 the adjacent ends of the two cars or sections A and B are without platforms and vestibules and in case small cars of the ordinary type are to be converted for use in the construction of one of my improved articulated cars, the vestibule and platform is removed from one end of each car for the purpose of accommodating the intermediate passenger carrying compartment C. Each of the cars A and B is provided at its outer end, or the 25 end distant from the intermediate compartment, with the usual platform and vestibule shown at *a* and *b* respectively, and for the sake of illustration in the car shown in Fig. 1 the entrance may be presumed to be 30 through the conductor's platform and vestibule at *a* while the exit is through the motorman's platform and vestibule at *b*. The intermediate passenger carrying compartment C is flexibly jointed or connected to the end 35 sections or cars A and B in the manner hereinafter described, so that the entire unit may readily take sharp curves and grades.

The end section A is provided with suitable seats as indicated at *a*² so that an aisle *a*³ is formed longitudinally through such section, while the intermediate compartment C is preferably formed with longitudinal seats *c* between which extends the aisle *c*'. The other end section B is provided with suitable 55 seats *b*² between which extends the longitudinal aisle *b*³. As will be seen by reference to Fig. 2 the aisles of the three sections A, B and C of the car form practically one continuous passage-way through the entire car, 60 the floors of the three sections being in the same horizontal plane or substantially flush as hereinafter described.

I will now proceed to explain how the intermediate compartment C is flexibly connected or jointed to the end sections A and

B, and as the connections between the intermediate compartment and one end section are similar to the connections between the intermediate compartment and the opposite end section, a description of one will suffice 70 for both.

The cross sill of the end section is shown at 1, while 2—2 are door posts at the sides of the door opening 3, leading to the intermediate compartment. The sill 1 at the center of the door-way is bored as at 4 which bore is enlarged at its upper end as at 5, the entire bore being lined with a bushing 6. Through this bushing is passed the coupling pin 7 the head 8 of which lies in the socket 5. 80 The lower end of the coupling pin passes through the bore 9 in the bolster 10 and is provided with the usual nut 11. Mounted upon the central portion of the bolster is a grooved plate 13 for the ball bearings 14, 85 while 15 designates a top plate grooved at 16 for the ball bearings 14. These balls are held in place in the groove or race-way of the top plate by the edges of the walls of the groove so that the balls are prevented from dropping out when the top plate is moved away from the bottom plate 13. As this manner of retaining the balls in the top plate is well known, it forms no part of the present invention. Fastened to this top plate 90 15 through the medium of bolts 17 is the end frame plate 18 of the supporting frame 19 of the intermediate passenger compartment. The coupling pin 7 as will be seen by reference to Figs. 7 and 8 passes through the 100 frame plate 18 and the ball bearing plates so that the frame is mounted to swing freely from side to side upon the ball bearing turn tables. A coil spring 20 is interposed between the frame plate 18 and the bottom of the sill 105 1 so that the relative vertical movement of the intermediate section and the end section is compensated for. The frame 19 which is connected to the compartment C by brackets 19' includes the diagonal brace members 21 110 which converge and merge into the end frame plate 18. From the above description it will be seen that the intermediate section and the end section may swing freely relatively to each other in taking curves, while 115 at the same time the vertical movement between the two sections may take place as when the car is ascending or descending a grade. In order to prevent the intermediate section from tilting or rocking too much at 120 one side or the other while the car is in motion, I provide a pair of oppositely disposed curved arms 22 the inner ends of which are connected by the cross bar 23 which is fastened beneath the bottom of the intermediate compartment. The arms 22—22 extend beneath the sill 1 of the end section and rest upon and work over roller bearings 24, 125 said arms being sufficiently long to insure that they will not be pulled forward and out 130

of engagement with the roller bearings when the intermediate section pivots or swings to the limit of its movement.

The sill 1 is formed with a pair of vertical sockets 25, preferably adjacent the door posts, these sockets opening through the top of the sill and through alining openings in the sill plate 26. Resting upon this sill plate 26 is the rear or straight edge portion 13 of the platform plate 27 which as will be seen by reference to Fig. 4 is approximately semicircular in form. This platform plate is horizontally secured to the sill plate and to the sill by means of bolts 28 which pass 15 through the rear end portion of the platform plate and into the sockets 25, these bolts being surrounded by coil springs 29 which normally tend to yieldingly hold the adjacent portion of the plate 27 in contact with 20 the sill plate under the vibrations of the moving car. The forward curved edge 30 of the sill plate overlaps the adjacent end of the compartment C and lies and works within a segmental groove 31 in the segmental strip or plate 32 which is bolted at 25 33 to the floor of the intermediate compartment. It will thus be seen that this platform plate 27 is substantially flush with and forms practically a continuation of the floors 30 of the aisles of the end section and the intermediate compartment of the car so that a passenger may pass from such end section to the intermediate compartment and vice versa along a uniform surface and without 35 stepping into wells or other depressions in the floor of the car. Furthermore it will be seen that by so mounting the platform plate upon the spring tensioned bolts and arranging the plate to work within the 40 slotted segmental strip, such platform plate is normally maintained in its flush position relative to the floors of the end section and the intermediate compartment under the vibrations and jars to which the car is subjected. In order to inclose the passage-way 45 between each end section of the car and the intermediate compartment thereof, I provide flexible vertically arranged curtains 34 which are attached at their ends 35 to the 50 door posts of the intermediate compartment the opposite ends of said curtains being wound about the rollers 36 supported at the side door of the end section, each of these rollers being preferably provided with a 55 pair of right and left hand springs so that the curtain will be automatically held taut. Each curtain roller is preferably incased by a vertical angular shield strip 37 which is fastened to the sides of the door of the end 60 section of the car. To prevent rain, dust and the like falling into the passage-way between each end section and the intermediate compartment, I hinge to each of such end sections as at 38 a hood 39 preferably in the 65 form of a plate the free end portion of

which rests upon the packing strip 40 lying in the groove of the rail 41. It will be noted that this hood plate is maintained in its covering position by gravity, and that as the intermediate section and the end section 70 change their relative positions as in taking a curve, the hood will ride or move over the packing strip 40. The sides of this hood plate 39 are also preferably provided with depending flap curtains 42 which overlie the 75 upper end portions of the side curtains 34 so that it will be seen that the entire passage-way between the intermediate compartment and the end section is inclosed by the side curtains, the top hood plate and the 80 top side flaps carried by the hood plate.

I am aware of the fact that it has hitherto been proposed to construct articulated cars wherein an intermediate section was interposed between two end cars or sections, but 85 in some cars of this type with which I am acquainted this intermediate section was employed simply as an entrance well or a conductor's platform and not as a passenger carrying compartment, and furthermore the 90 floor of such car was arranged below the level of the floors of the end sections so that it was necessary for the passenger to step down into the well or floor of the intermediate section and then up and into the end 95 sections of the car. Other cars or trains having an intermediate section have employed such section, either merely as a vestibule, or have provided it with trucks or other traction devices for engaging with and 100 traveling on the track, so that in the latter case such an intermediate section really constituted a separate car having its own traction devices. So far as I am aware I am the first to provide an articulated car where- 105 in a pair of end passenger-carrying units or sections carry, flexibly supported or hung between their confronting or adjacent ends, an intermediate passenger-carrying compartment which is supported solely by the 110 end sections in the sense that it is not pro- 115 vided with trucks or other traction devices, and in which articulated car the aisles or floors of the end sections and the intermediate compartment lie in substantially the same horizontal plane so that a continuous passage-way is formed entirely through the car with the entrances and exists at the end sections of the articulated car.

The numerous advantages incident to my 120 improved car will be readily apparent to those familiar with railway rolling stock equipment and the requirements and opera- 125 tion thereof. It will be noted that although I attain a greatly increased passenger carry- 130 ing capacity the expense of operating the car is no more than the usual street car, for all the service that is required is that of one conductor and one motorman. Furthermore it will be noted that my car is so con-

structed that it may readily and easily take steep grades, sharp curves and the like and that it may travel over standard track-ways, through crowded cities and towns without requiring any changes in the construction of such track-ways.

While I have herein shown and described one particular embodiment of my invention I wish it to be understood that I do not confine myself to all the precise details of construction, herein set forth, as modification and variation may be made without departing from the spirit of the invention or exceeding the scope of the appended claims.

15. What I claim is:

1. In an articulated car, the combination with a pair of end sections, of an intermediate compartment flexibly suspended between and supported by the adjacent ends of the 20 end sections, the floor portions of the end sections and the intermediate compartment all lying in substantially the same horizontal plane.

2. In an articulated car, the combination with a pair of end sections, of an intermediate compartment suspended from and flexibly connected with the adjacent ends of the end sections, said intermediate compartment having closed side walls, the end sections of 30 the car having door-ways for passengers at their ends distant from the intermediate compartment, the floors of the end sections and the intermediate compartment all lying in substantially the same horizontal plane.

3. The combination with a pair of end sections, of an intermediate compartment suspended from and flexibly connected with the adjacent ends of the end sections, and having closed side walls, said end sections having door-ways therein for the admission 40 and exit of passengers.

4. The combination with a pair of end sections, of an intermediate compartment suspended from and supported by the end sections, and capable of vertical and lateral 45 movement relative to the end sections, a continuous aisle being formed through all of said sections with the floor portions of said aisle lying in substantially the same horizontal plane.

5. The combination with a pair of end sections, of an intermediate compartment flexibly suspended between and supported by the end sections, a continuous passage-way being formed through the end sections and the intermediate compartment, a platform plate carried by each end section and movably connected with the intermediate compartment, and means for inclosing the side and top spaces between the compartment 55 and the end sections.

In testimony whereof, I affix my signature, in the presence of two witnesses.

ALPHONSO TAURMAN.
